Patented Nov. 12, 1963

196,867

BOTTLE CAP REMOVER

La Vergne H. Williams, Columbia, Conn.

Filed July 17, 1962, Ser. No. 70,961

Term of patent 3½ years

(Cl. D44—29)

FIG. 1 is a perspective view of a bottle cap remover embodying my new design; and

FIG. 2 is a perspective view showing the opposite side thereof.

I claim:

The ornamental design for a bottle cap remover, as shown.
